(57) **CLAIM**

We claim the ornamental design for a screen, as shown and described.

DESCRIPTION

FIG. 1 is a front perspective view of the screen mounted on a chair, wherein two horizontal straps and a vertical strap are connected together;

FIG. 2 is a rear perspective view of the screen mounted on the chair, wherein two, vertically-arranged tensioning straps are disconnected from respective sets of mating strips mounted on a main panel of the screen;

FIG. 3 is a front planar view of the screen, wherein the two horizontal straps and the vertical straps are disconnected from one another; wherein either hook or loop fasteners are shown arranged on strips mounted on one of the horizontal straps and on the vertical strap;

FIG. 4 is a front planar view of the screen, wherein the two horizontal straps and the vertical straps are connected together;

FIG. 5 is a rear planar view of the screen, wherein the two, vertically-arranged tensioning straps are connected to respective sets of mating strips mounted on the main panel of the screen;

FIG. 6 is a rear planar view of the screen, wherein the two, vertically-arranged tensioning straps are connected to respective sets of mating strips mounted on the main panel of the screen; and,

FIG. 7 is a section taken along section lines 7-7 in FIG. 3. The screen is useful for mounting on a chair. When the person sitting on the chair in front of a webcam, the screen can block the view behind the person. The tensioning straps on the back can be selectively engaged and disengaged with mating strips to enhance the degree that the screen retains a vertical orientation.

In the drawings, the broken lines in FIGS. 1 and 2 depict a chair and form no part of the claimed design.
